UNITED STATES PATENT OFFICE

WALDO L. KRAMER, OF BROOKLYN, NEW YORK, ASSIGNOR TO KEARFOTT ENGINEERING COMPANY, INC., A CORPORATION OF NEW YORK

WEATHERTIGHT SHIP'S WINDOW

Application filed March 29, 1930. Serial No. 433,871.

My invention relates to windows. In particular the invention is directed to a weather-tight ship's window.

Commonly, windows of this type comprise a frame member having a window opening therein. Behind the frame member and spaced therefrom a window-pane guideway is provided. In the guideway, a frameless window-pane is slidably mounted and window-pane traversing means are provided for raising and lowering the window-pane in the guideways. When the window-pane is in closed position, the upper and side edges thereof are received in the guideway and form a substantially weathertight connection therewith. These windows, however, are objectionable for the reason that in rough and stormy weather, even when the window-pane is in closed position, water will enter between the frame member and the window-pane and also under the lower edge of the window-pane and enters the structure below the window and subjects that structure to alternate periods of dampness and dryness in accordance with the prevailing weather conditions.

By my invention, I am enabled to construct a ship's window of this type which, in the closed position of the window-pane, is weathertight. I employ a construction which comprises a frame of rectangular window shape. In contact with the inner surface of this frame, the window-pane guideway is secured. Thus, there is no space between the frame and the guideway into which water may enter. In order to prevent water and the like from entering under the lower edge of the window-pane, I provide a jamming member which is secured to the lower end of the window-pane. The jamming member has an inclined surface which cooperates with a complementary surface formed on the lower edge of the frame of window shape.

An advantage of my construction is the fact that the inclined surface of the jamming member acting against the inclined surface on the frame member forces the window-pane tightly against the guideway.

Other advantages of my invention will ap-

pear from the following particular description of one embodiment thereof taken in connection with the accompanying drawings in which:

Fig. 1 is an elevation of a window constructed in accordance with my invention;

Fig. 2 is an enlarged sectional elevation of the same taken on the irregular line 2—2 of Fig. 1; and

Fig. 3 is an enlarged fragmentary sectional elevation.

In the drawings, I have illustrated a window which comprises a frame member of window shape which is adapted to be secured to a wall 2 by means of machine screws 3. The frame member 1 is preferably made of brass and has inwardly and outwardly extending flanges 4 and 5 which define the window opening therein. That portion of the inwardly extending flange 2 which defines the bottom of the window opening is provided with an inclined surface 6, the purpose of which will hereinafter appear.

To the inner surface of the frame member 1 there is secured a rectangular frame of L-shape in cross section, one flange 8 thereof being secured to the window-shape frame member 1 and the other flange 9 extending laterally therefrom. A guideway 10 is secured to this flange 9 of the L-shape frame.

The guideway 10 is U-shape in cross section and is secured to the flange 9 by means of machine screws 11 extending through the web of the guideway. The edges of one leg of the U-shape guideway contacts with the inwardly extending flange 4 of the window-shape frame member 1 along the upper and side edges of the window opening therein, the guideway extending downwardly along the sides of the L-shape frame beyond the window-shape frame 1. The guideway is preferably lined with some flexible material 12 such as felt, and is adapted to guide a frameless window-pane 13 which is slidably mounted therein.

The window-pane 13 is adapted to be moved in the guideways to open and close the window and for this purpose a transversing mechanism is provided. The lower edge of the window-pane is secured in a clamp mem-

ber 14, a rubber lining 15 being interposed between the metal and the window-pane. To the bottom of this clamp member 14, a member 16 is secured by means of machine screws 17. The member 16 extends downwardly from the clamp 14 and is provided with lateral projections 18. These lateral projections engage a collar 19 formed integral with the lower edge of a nut 20 which is threaded on a screw shaft 21. The nut is also provided with an integral projection 22 which is adapted to be received in an opening in the member 16. Thus, movement of the nut along the screw shaft moves the window-pane 13.

15 The screw shaft 21 is journaled at the upper end thereof in a thrust bearing 22 secured to a cross member 23 which extends between the sides of the L-shape frame member substantially at the center thereof. At the lower end, 20 the screw shaft is journaled in the lower cross member of the L-shape frame member. At the upper end of the screw shaft, there is secured a beveled gear 24. The beveled gear 24 meshes with a similar gear 25 secured on the 25 end of a transverse shaft 26 which is journaled at one end in a bearing bracket 27, and is journaled at the other end in a bearing bracket 28. A second beveled gear 29 is secured to the opposite end of the shaft 26 and 30 meshes with a corresponding gear 30 secured on the end of a short shaft 31 which is journaled in a bearing bracket 32. The bearing brackets 28 and 32 are supported by an extension of the cross member which extends 35 beyond the side of the L-shape frame member, the flange 9 of the L-shape frame member being cut away at this point. On the end of the stub shaft opposite the end to which the beveled gear 30 is secured, a handle 33 is secured. Through this train of mechanism, 40 rotational movement of the handle 33 is transmitted to the screw shaft 21 and rotational movement of the screw shaft raises or lowers the nut depending upon the direction of rotation of the screw shaft.

45 A jamming member 34 is secured against the outer surface of the window-pane 13 adjacent the lower edge thereof. As shown on Figs. 2 and 3, the jamming member is an integral part of the flexible lining 15 which extends along the lower edge of the window pane and has an extension along the outer surface of the clamping member. The jamming member extension along the outer surface of the clamping member is secured to the side of the clamping member by a plate and machine screws 35 which extend through the plate and into the clamping member. The jamming member is preferably made of some pliable material, such for instance as rubber, and is provided with an inclined surface 36 converging toward the surface of the window-pane. This inclined surface is complementary to the surface 6 formed on the lower portion of the inwardly extending flange 4

defining the window opening in the window-shape frame member 1. When the window-pane is raised to the closed position, the inclined surface 36 of the jamming member 34 cooperates with the inclined surface 6 on the inwardly extending flange 4 of the window-shape frame member 1 to exclude all manifestations of the elements, which would otherwise enter at this point. The jamming member also serves to press the window-pane against the flexible lining of the guideway, thereby making the window, in the closed position, substantially weathertight.

It is obvious that various changes may be made in the illustrated embodiment above particularly described by those skilled in the art within the principle and scope of my invention as expressed in the appended claims.

Claims:

1. In a window of the character described, a frameless window-pane, window-pane traversing means including a clamping member adapted to clamp the lower edge of the window-pane, and a flexible lining between the window-pane and the clamping member having an enlarged portion above the clamping member, said enlarged portion forming a jamming member.

2. In a window of the character described, a frameless window-pane, window-pane traversing means including a clamping member adapted to clamp the lower edge of the window-pane, and a flexible member comprising a portion extending around the lower edge of the window-pane between the window-pane and the clamping member, an enlarged portion above the clamping member having an inclined surface and constituting a jamming member, and a portion extending from said enlarged portion along the outside of the clamping member, and means for securing said latter portion to the clamping member.

3. In a window of the character described, a frameless window-pane, window-pane traversing means including a clamping member adapted to clamp the lower edge of the window-pane, and a flexible member comprising a portion extending around the lower edge of the window-pane between the window-pane and the clamping member, an enlarged portion above the clamping member having an inclined surface and constituting a jamming member, and a portion extending from said enlarged portion along the outside of the clamping member, a plate extending along the latter portion, and means for clamping said portion between the plate and the side of the clamping member.

4. A weathertight ship's window comprising a metal frame member of substantially twice the length of the window opening, another frame member of window shape secured to the upper portion of said first mentioned frame member, said window shape frame be-

ing adapted to be secured to the side of a ship and having inwardly and outwardly extending lateral flanges defining the window opening therein, window-pane guideways of 5 channel-shaped in cross-section secured to the inner surface of the sides and top of said first mentioned frame member, a frameless window-pane slidably mounted in the window-pane guideways, traversing means for the 10 window-pane including a clamp adapted to clamp the lower edge of the window-pane, a flexible jamming member secured to said clamp and lying against the outer surface of the window-pane, and a cooperating complementary surface on the window-shaped frame member along the lower edge of the lateral inwardly extending flange thereof.

15 In witness whereof, I hereunto subscribe my signature.
